UNITED STATES PATENT OFFICE.

LELAND L. AWTREY, OF WAXAHACHIE, TEXAS.

RUNNING-GEAR FOR PLOWS.

No. 904,039.

Specification of Letters Patent.

Patented Nov. 17, 1908.

Application filed December 26, 1907. Serial No. 408,115.

To all whom it may concern:

Be it known that I, LELAND L. AWTREY, a citizen of the United States, residing at Waxahachie, in the county of Ellis and 5 State of Texas, have invented a new and useful Running-Gear for Plows, of which the following is a specification.

This invention has relation to running gear attachments for plows and it consists 10 in the novel construction and arrangement of its parts as hereinafter shown and described.

The object of the invention is to provide an attachment in the form of a running gear 15 which is adapted to be easily and readily applied to the beam of a plow or similar implement whereby the implement is converted from one of the walking type into one of the sulky type.

20 The running gear is mounted upon wheels and means is provided for steering the same. Means is also provided for raising and lowering the implement with relation to the wheels.

25 In the accompanying drawings: Figure 1 is a side elevation of a plow equipped with the running gear with parts thereof broken away. Fig. 2 is a front elevation of the same, and Fig. 3 is a top plan view 30 of the same.

The running gear consists of the bolster 1 which is made up of parallel spaced bars. Said bolster is provided at its ends with the bearings 2 in which are journaled the spindles 3. The spindles 3 may move longitudinally in the bearing 2. The furrow wheels 4 are journaled for rotation at the lower ends of the spindles 3 and are disposed in synclinal relation to each other.

40 The saddle 5 is mounted upon the bolster 1 and may be adjusted longitudinally thereof and when properly adjusted is secured in place by the clamp bolts 6. The beam 7 rests upon the saddle 5 and is adjustably 45 secured thereto by means of the clamp bolts 8. The seat post 9 is bolted or otherwise secured to the beam 7. The arm 10 is attached to the rear portion of the beam 7 and the caster wheel 11 is journaled in the 50 arm 10.

The forwardly disposed arms 12 are attached to the bearings 2 and the forward ends of the levers 13 are fulcrumed to the arms 12. The gear segments 14 are also 55 mounted upon the bearings 2 and the levers

13 are provided with spring pawl mechanisms 15 which are adapted to engage the gear segments 14. The arms 16 are fixed to the upper ends of the spindles 3. Each arm 16 is provided at its end which attaches with 60 the spaced portion 17 and the blocks 18 are journaled upon the upper ends of the spindles 3 and lie between the upper surfaces of the spaced portions 17 thereof. The links 19 65 pivotally connect the levers 13 with the blocks 18. The standard 20 is attached to the beam 7 and is provided at its upper end with a gear segment 21. The lever 22 is fulcrumed to the standard 20 and the links 70 23 connect the lever 22 with the arms 16. One of the links 23 connects with the lever 22 upon one side of its fulcrum point, while the other link 23 connects with the lever 22 upon the opposite side of the fulcrum point 75 thereof. The lever 23 is provided with a spring actuated pawl 24 which is adapted to engage the gear segment 21. The links 23 are pivotally connected at their opposite ends to the parts with which they connect. 80

From the foregoing description it is obvious that by loosening the clamp bolt 6 the bolster 1 may be shifted laterally under the beam 7 so that the furrow wheels 4 may be properly positioned with relation to the 85 beam. This adjustment may be accomplished without disconnecting the links 23. When the bolster has been properly adjusted, as above described, it is secured by tightening the bolt 6. When it is desired to 90 adjust the beam 7 vertically with relation to the wheels 4 the levers 13 are operated which move the bearings 2 along the spindles 3. Should it be desired to adjust one of the ends only of the bolster 2 in a vertical direction 95 with relation to the furrow wheels but one of the levers 13 is operated. It is also obvious that by moving the lever 22 that the spindles 3 will be turned axially through the instrumentality of the arms 16 and levers 23, thus 100 the ground wheels 4 are steered but are always disposed in the same relation toward each other.

Having thus described my invention, what I claim as new and desire to secure by 105 Letters-Patent is:—

In a device of the kind described, a bolster, sleeves held upon the ends thereof, wheels provided with pin axles extending through said sleeves and adjustable therein for 110

height and angular relation to said bolster, means for separately adjusting each of said wheels with reference to its height, a beam transversely disposed with relation to the 5 bolster and adjustably mounted thereon, a latch lever held upon said beam, arms mounted on said axles, and links connecting the said arms to said latch lever arranged to hold the wheels from angular variation as 10 the beam is adjusted on the bolster, and to

vary such angular relation to the line of draft at the will of the operator.

In testimony that I claim the foregoing as my own, I have hereto affixed my signature in the presence of two witnesses.

LELAND L. AWTRY.
